[57] CLAIM

The ornamental design for a bathing enclosure for a bathtub, as shown and described.

DESCRIPTION

FIG. 1 is a perspective view taken from the top and front of a bathing enclosure for a bathtub showing my new design;

FIG. 2 is a top plan view thereof;

FIG. 3 is a front elevational view thereof;

FIG. 4 is a cross-sectional view taken on line 4-4 of FIG. 3; and,

FIG. 5 is a fragmentary cross-sectional view taken on line 5-5 of FIG. 2.

The fragmentary broken line representation of bathroom walls in FIG. 1 and the broken line representation of openings in FIGS. 1 and 4 are for purposes of illustration only and form no part of the claimed design.
